UNITED STATES PATENT OFFICE

2,035,031

ADJUSTABLE FASTENER

Gustav von Koczian, Berlin, Germany

Application June 25, 1934, Serial No. 732,323
In Germany July 1, 1933

3 Claims. (Cl. 24—206)

This invention relates to an adjustable fastener for belts, garments, bags or the like. More particularly the invention refers to that type of fastener, in which there are provided on the one part of the article to be secured a series of catches or abutments, over which there is passed a slide-like locking member secured to the second part of the said article.

Heretofore it has been usual to employ for the catches smooth pieces of wire or sheet metal on a flexible supporting band. These pieces of wire or sheet metal are preferably clamped to the folded middle portion of the band.

The known catches or abutments reveal various disadvantages. For example, they do not permit sufficiently firm engagement on the part of the slide member, so that when even a relatively slight pull is exerted on the fastener the slide member will be withdrawn from the catches and the fastener accordingly released. This disadvantage will be found to exist both when the pieces of wire or metal are clamped to the folded middle portion of the supporting band as well as when the same are secured to the said band in immediate fashion, since in either case the pieces of wire or sheet metal do not project a sufficient extent away from the surface of the band to provide a sufficient hold for the slide. Further in the majority of cases it is necessary to employ for the wire or metal members a special supporting member, which in turn requires to be affixed to the article concerned, unless the parts are produced on the article during the manufacture itself, as in the case of a lightning fastener.

It is the object of the invention to overcome the disadvantages associated with the known forms of embodiment, and this is accomplished by making the catches in the form of mushroom headed studs forming guide means for a slidable buckle of double-channel shaped cross-section embracing the heads. When closing the fastener the buckle will find a secure hold against one of these studs, so that the fastener cannot be released even when a strong pull is exerted on the same. Further the stud-like catches do not call for a special supporting member, but may be applied in direct fashion to the article to be secured, and as they constitute the sole guide means for the buckle, the latter need not engage the edges of the belt or other article whereby wear of said edges is prevented.

The fastener according to the invention may be employed for an extremely large number of articles.

The invention will now be described more fully with reference to the accompanying drawing, in which

Fig. 1 is a perspective view showing the fastener secured to a belt.

Fig. 2 is a plan view of the fastener.

Fig. 3 is a longitudinal section through the same, and

Figs. 4, 5 and 6 illustrate different forms of the stud-like catches.

To the belt 1 there are secured, one behind the other, a series of headed stud-like catches spaced a suitable distance apart. The studs 2 possess a neck portion 2', and may be secured to the belt 1, for example, by folding over the extensions 2''.

The belt 1 is secured with the assistance of the slide-like buckle 3. The lower part 4 of the slide 3 possesses a guide 5 corresponding with the cross-sectional form of the headed studs 2, so that the slide 3 embraces the necks 2' of the studs 2.

Within the slide there is located a spring 6, which is bent over at the front end 6' to form a nose capable of engaging in the space between two studs 2. The opposite end of the spring 6 is secured to a plate 7 possessing a bulged portion 9 adapted to support the spring 6. The same is moved by a slide button 8.

The slide 3 is secured by a keeper 10 to the opposite end of the belt 1.

To permit numerous possibilities of fastening or adjusting the belt 1 there may be provided any desired number of studs 2. The slide or buckle 3 is passed over the studs 2, and is locked in position at any point where studs may be provided when, by means of the button 8, the end 6' of the spring 6 is moved into the space between two studs. To open the fastener the button 8 is moved into the position of rest shown in Fig. 3 in broken lines. The tensioning of the spring 6 takes place over the bulge 9. In the position of the button 8 indicated in broken lines the slide 3 is able to pass freely over the studs 2.

The stud 2 may be made in various forms. In Fig. 4, for example, the same possesses a rounded head. In Fig. 5 the stud is made in the form of a rivet 11, the upper portion 11' of which may be covered with textile or any other material. The head may also be composed of artificial resin or other colored material, and in fact the studs, if desired, may be adapted in their appearance to the particular article to which they are secured. In Fig. 6 the stud possesses a head 12 of greatly rounded form.

What I claim as new and desire to secure by Letters Patent is:

1. Adjustable buckle fastening for belts, garments, pouches, and like articles comprising a row of studs mounted on one end of the belt and each stud having head and neck portions, a slide mounted on the other end of the belt and guided on the studs over the heads and embracing the necks of a plurality of said studs, and means cooperating with the studs for releasably locking the slide against any desired stud.
2. Adjustable buckle fastening for belts, garments, pouches, and like articles comprising a row of mushroom headed studs having neck portions and mounted on one end of the belt, a slide of substantially U-shaped cross-section mounted on the other end of the belt and being adapted to pass over the heads and embrace the necks of a plurality of said studs, whereby said slide is guided on the studs, and means coop-

erating with the studs for releasably locking the slide against any desired stud.

3. Adjustable buckle fastening for belts, garments, pouches, and like articles comprising a row of studs mounted on one end of the belt and each having head and neck portions, a slide mounted on the other end of the belt and guided on the studs by passing over the heads and embracing the necks of a plurality of said studs, and means cooperating with the studs for releasably locking the slide against any desired stud, said means including a spring in the slide having a nose capable of entering spaces between the studs and a button movable between locking and unlocking positions, said button in its locking position positively holding the nose of the spring in one of said spaces and in its unlocking position permitting said nose to ride over the studs.
